SEQUIN BOW

Irving Schlossberg, Brooklyn, N. Y., assignor to
Consolidated Sequins Corp., New York, N. Y., a
corporation of New York

Application May 28, 1948, Serial No. 146,668

Term of patent 3½ years

(Cl. D3—32)

To all whom it may concern:

Be it known that I, Irving Schlossberg, a citizen of the United States of America, residing at Brooklyn, in the county of Kings and State of New York, have invented a new, original, and ornamental Design for a Sequin Bow, of which the following is a specification, reference being made to the accompanying drawing, forming a part thereof.

Fig. 1 is a front view of a sequin bow, showing my new design;

Fig. 2 is a rear view thereof; and

Fig. 3 is a side view thereof.

I claim:

The ornamental design for a sequin bow, substantially as shown.

IRVING SCHLOSSBERG.
